UNITED STATES PATENT OFFICE.

RALPH I. PENDLETON, OF DENVER, COLORADO.

AUTOMATIC FLUID-PRESSURE DISPLACEMENT PUMP.

Application filed May 15, 1923, Serial No. 639,119. Renewed August 7, 1925.

This invention relates to automatic fluid pressure liquid displacement pumps of a type wherein an operating pressure fluid, such as compressed air for instance, is admitted into a displacement zone adapted to receive charges or volumes of the incoming liquid to be pumped, the said operating pressure fluid functioning as a fluid piston to force said liquid through an outlet conduit 10 suitably leading from said displacement zone, and the inflow of both said pressure fluid and said liquid being under such an automatically coacting valvular control that the one is cut off as the other is being admitted into said displacement zone.

Although the invention primarily has been devised for the individual pumping of oil wells, as contradistinguished from the more or less complex pumping riggings generally operated in balanced sets in highly productive fields, the many disadvantages of which are well understood by those actively engaged in the productive end of the oil industry and which need not therefore be entered into, and while the improvements will accordingly be more particularly disclosed with reference to oil well pumping, still it is nevertheless to be understood from the outset that the use of the invention is not necessarily to be limited to this one special field of employment, as the improvements might well be adapted for installation in other analogous relations and for the pumping of other liquids than oils.

It has heretofore been proposed to employ displacement pumps, of the character set forth, with which both the inflow of the liquid to be pumped and the operating pressure fluid are, broadly speaking, under the automatic control of valvular means located within the displacement chamber of the pump, and by the present invention I also follow said principles broadly, but no claim is made herein to any such arrangements involving or embodying a paired set of valvular parts, one of which has a portway co-operating with a plurality of ports provided by its casing, for controlling the inflow of the operating pressure fluid, and the other 50 of which controls the inflow of the liquid to be pumped.

The primary object of the present invention is to simplify former constructions, not only for the purposes of decreasing the costs of manufacture and installation but also with the aims of prolonged durability, maxi-

mum efficiency and economy in operation, and material reductions of expenses for maintenance and repairs.

The foregoing and other objects and advantages, as well as the manner and means for accomplishing the desired ends, will be so clearly apparent, as incidental to the following disclosure, that it would only be undesirable surplusage and would serve no useful purpose to further enlarge upon the same initially, so that reference will now be immediately had to the accompanying drawings, illustrating certain practical embodiments of the improvements, which drawings 70 form a part of this specification and in which—

Figure 1 is a central longitudinal sectional view through the pump and its associated parts as applied within a well casing and with its sole operating valve part, common to both pressure fluid and liquid inlets, shown seated in its lowermost position, shutting off the liquid inflow and admitting the operating pressure fluid into the displacement zone, the view being partly illustrated as broken away and with the upper section thereof further showing the application of a reduced discharge or outlet conduit, with packer means therefor, which 85 may be employed when production decreases.

Figure 2 is a view analogous to Figure 1, but with the operating valve part seated in its uppermost position, shutting off the operating pressure fluid from the displacement zone and admitting the liquid to be pumped therein.

Figures 3 and 4 are longitudinal central sectional views, substantially analogous to Figure 1 but respectively illustrating certain modifications in the construction, arrangement and disposition of the operating pressure fluid conduit and the outlet or discharge conduit for the liquid, leading to and from the displacement zone, which displacement zone does not now partially include the well casing chamber, so that no packer means are required.

Figures 5 and 6 are cross-sectional views taken, respectively, along the planes of the lines 5—5 and 6—6 of Figure 1.

Figures 7 and 8 are cross-sectional views taken, respectively, along the planes of the lines 7—7 and 8—8 of Figure 3, and

Figures 9 and 10 are cross-sectional views taken, respectively, along the planes of the lines 9—9 and 10—10 of Figure 4.

Referring first to Figures 1, 2, 5 and 6, although in all of the views the same parts will be designated by the same reference characters where feasible, the numeral 14 indicates the lower portion of a well casing into which there is downwardly inserted the casing of the valve chamber 15 of the pump. Although the expression "well casing" is used for convenience, it is to be understood that, wherever herein I employ the same, it equivalently applies to well tubing as well, if such tubing is run down within the well casing proper.

This valve chamber casing may be formed as an open-ended barrel 16, with the ends thereof preferably threaded internally, as at 17 and 18, to respectively receive the externally threaded valve chamber head 19 and the open-ended cylindrical bottom extension 20.

The lower portion of the bottom extension 20, protruding below the valve chamber casing 16, is encompassed by a packer or gasket 21, adapted to snugly fit the inside of the well casing 14, and the other end thereof terminates in an upwardly disposed internal edge valve seat 22, complementary of the operating valve element 23 as the controlling means for the inflow of the liquid to be pumped.

The packer ring or gasket 21, snugly interposed between and in conjunction with the cylindrical extension 20 and the well casing 14, provides the well casing with separated chambers or divisions, and obviously the liquid to be pumped enters from the lower division, below the gasket 21, thence flowing upwardly within the hollow extension and under valvular control into the displacement zone. The displacement zone in this instance embraces not only the valve chamber 15 itself but also the upper division 24 of the well casing, indicated above the packer 21 and likewise above the barrel head 19, and in this construction the well casing serves as the outlet or discharge conduit for the pumped liquid. Entrance from the valve chamber 15 into the well casing division 24 is provided for by a lateral series of apertures or ports 25, through the wall of the valve chamber above the seat 22, and by a vertical series of apertures, bores or ports 26 extending through the valve chamber head 19. The apertures 25 may not be strictly essential, or they might be arranged at a higher position and the vertical apertures 26 dispensed with, but for maximum efficiency it is believed that the inclusion of both sets of apertures as disclosed would be most desirable.

The valve chamber head 19 is provided with a substantially large central bore 27 that is preferably threaded to receive at its upper portion the threaded lower end of the operating pressure fluid conduit pipe 28, and

at its lower end to receive an open-ended detachable nozzle member 29, the interior of which is preferably of downwardly converging conical or tapering form, as is indicated at 30, and terminates in or merges into a valve seat 31, downwardly disposed oppositely to and substantially spaced from said valve seat 22, which valve seat 31 is complementary of the operating valve element 23 as the controlling means for the inflow of the operating pressure fluid into the displacement zone.

It may be emphasized here that the bore of the pressure fluid inlet pipe 28 is of smaller cross-sectional area than the bore of the liquid inlet conduit 20, or at least that the cross-sectional area of the discharge orifice of the nozzle 29 and its terminal valve seat 31 are relatively less than those of the valve seat 22.

The said valve element 23 could be other than of the particular spherical form shown, and for instance it could be in the nature of an integral pair of reversed base to base cones, in which case the form of the valve seats would be altered accordingly, but for practical purposes it would doubtless be preferable to employ a ball valve element as illustrated. At all events, the said valve element 23 operates in truly balanced relation, owing to the relative difference in cross-sectional area of the discharge openings or orifices upon which it acts, and it is the one and only operating valve part employed, although functioning dually between the two valve seats, and being common to or complementary of both of said valve seats, 31 and 22, these seats may appropriately be referred to, respectively, as an upper and a lower valve seat, or as terminal valve seats, respectively, of the pressure fluid inlet and of the liquid inlet.

The nozzle element 29 is made detachable as stated, the object thereof being primarily for interchangeable purposes. It is believed that this feature is of considerable importance, and is claimed as a part of the invention, inasmuch as it permits of a nozzle having a larger or vice versa a more restricted discharge orifice or outlet to be substituted the one for the other, thereby proportionately regulating the cross-sectional area of the operating fluid pressure on the valve 23, when up against its seat 31, relatively to the cross-sectional area of the liquid pressure on the underneath surface of the valve, or allowing for the adjustment or changed control of the volume of the pressure fluid admitted to the displacement zone, during a given time, proportionately to the charges or volume of liquid to be pumped at each operation.

At the upper portions of the broken-away views of Figures 1 and 2 there are shown a pipe conduit 32 and a packer ring or gasket

33 encompassing the lower end thereof in snug contact with the well casing, but these additions are only supplied when the production of the well decreases, and will be 5 more particularly referred to in the description of the operation.

In the modified construction of Figures 3, 7 and 8, the broader principles involved are the same as those previously described, 10 but in this modified arrangement the well casing is never employed as the outlet conduit for the pumped liquid, no packer means are employed, and the pressure fluid conduit is disposed within the discharge or outlet 15 conduit for the pumped liquid. The manner of installing this modified arrangement is also different from the method employed in the previously described arrangement, and accordingly certain structural features 20 are also slightly altered, as will now be pointed out.

The packer ring or gasket not being used, the bottom cylindrical member 20, which supplies the valve seat 22, need not be as 25 long as heretofore, and the valve chamber head 19 has certain additional features.

In this construction the valve chamber head 19 is shown as having an integrally joined central downwardly disposed nozzle 30 element 35, providing the upper valve seat 31, and it does not show its bore as tapering, but it is obvious that this nozzle element might readily be altered to conform with and function as the interchangeable 35 nozzle element 29 of Figures 1 and 2. The valve chamber head is also provided with an upwardly disposed central tubular element 36, preferably having an annularly beveled upper edge face 37, and 38 indicates 40 the central bore that extends through the head 19 and nozzle 35 in registration with said tubular element 36. The head 19 additionally provides an outer upwardly disposed cylindrical extension 39, which is preferably internally threaded, as at 41, to receive the lower externally threaded end of the discharge or outlet conduit pipe 40 for the pumped liquid. 42 designates the pressure fluid conduit pipe which has a downwardly flaring annular lip 43 at its lower 45 extremity that is adapted to be seated upon the annularly beveled top edge face 37 of the upstanding tube 36 in pressure-tight relation, as will be later referred to in the description of operations and the manner of 50 installation.

In the further slightly modified construction of Figures 4, 9 and 10, the same remarks substantially apply as stated in connection 55 with Figures 3, 7 and 8, and with more particular reference to the broader principles involved being practically the same in all instances. The well casing is not employed as the discharge pipe for the pumped liquid, the packer ring or gasket 21 is omitted, the

bottom cylindrical member 20 may accordingly be of shorter length, and the nozzle element obviously is susceptible of alterations to make it detachable or interchangeable and otherwise conformable to the functioning of the nozzle of Figures 1 and 2. The pressure fluid pipe line, however, is not disposed within the discharge pipe line for the pumped liquid, so that certain changes are made which will now be more specifically 75 described.

The valve chamber head 19 may be partially threaded within the valve casing wall 16, and provides the downwardly projected central nozzle element 45, terminating in the upper valve seat 31, and the offsetting or upwardly slanting central extension 46, terminating in the upwardly directed offset nipple 47, the said extension 46 having a longitudinal bore 48 opening to the hollow 85 nipple 47, which is preferably internally threaded, and to the central bore 38 of the nozzle 45. Encompassing the upper portion of the head 19, either in threaded relation or it might be formed integral therewith as 90 in Figure 3, is an upstanding outer cylindrical extension 49, preferably internally threaded at its upper end, for the reception of a plugging head 50, which latter is provided with a pair of threaded apertures 51 and 52 for respectively receiving the lower end of the liquid discharge pipe 53 and of the pressure fluid pipe line 54, the latter being disposed exteriorly of the former, and the lower extremity of the pipe 54 may also 100 be threaded into the hollow nipple 47.

It will be noted that the lateral apertures 25 of Figures 1, 2 and 6 are naturally dispensed with in both of the modified constructions, wherein the well casing is not 105 employed at any time as the discharge or outlet conduit for the pumped liquid, and it is to be particularly emphasized, as to all of the arrangements, that the single operating valvular element 23 has no ports or portways whatsoever.

With reference to installation and operation, and first considering Figures 1 and 2, the pump as a unitary assembled whole, with the gasket 21 fitted around the lower 115 end of the bottom cylindrical member 20, is lowered or forced down into the well casing, as far as may be desired, by means of the attached fluid pressure line pipe 28.

As thus located, and assuming that the pressure fluid, furnished from any suitable source, is being uninterruptedly supplied at all times under a constant pressure into the line 28, which is the manner of its supply and that the well is substantially productive, so that it is not necessary as yet to install the pipe line 32 and the gasket 33. Then, with the valve 23 located at the position shown at Figure 1, the inflow of liquid to the displacement zone is shut off while the pres- 120 125 130

sure fluid is being admitted with full force, and hence the volume of liquid as previously charged into the displacement zone, embodying the valve chamber 15 and the well casing division 24 above the lateral apertures 25, is forced up within the well casing, serving as its discharge outlet conduit, by the incoming pressure fluid functioning as an elevating fluid piston.

10 This functioning will continue until the pressure on the upper surface of the valve 23 is equalized and slightly exceeded by the pressure of the well liquid upon the under surface of the said valve, whereupon the latter will be forced upwardly from its lower or liquid inlet seat 22 and into fluid tight relation with its upper or pressure fluid inlet seat 31, as illustrated at Figure 2. It follows, therefore, that the liquid inflow to the displacement zone will have been automatically established while the pressure fluid inflow thereto is being automatically and concurrently shut off, and which latter is then maintained shut off 25 for the time being by virtue of the difference in pressure area afforded by the nozzle injector orifice relatively to the liquid inlet opening, and hence the unbalanced pressures upon the upper and lower surfaces of 30 the operating valve part.

The filling up of the displacement zone with liquid from the well, as heretofore described, will then continue until the pressure downwardly upon the restricted upper 35 surface of the valve 23, which pressure fluid is partially controlled by the tapering form of the nozzle bore 30, and as augmented by the weight or pressure of the column of liquid above the valve part 23, will have 40 equalized or balanced the upward pressure of the well liquid upon the lower surface of said valve part, whereupon the latter will fall by gravity into liquid tight association with its lower or liquid inlet valve seat 22, 45 concurrently with the automatic opening up of the pressure fluid inlet with the displacement zone, when pumping will again be started and effected as before set forth.

50 These alternating or cyclical operations will therefore be automatically maintained indefinitely, just as long as the operating fluid is on and the flow of the well is under substantial pressure, and furthermore the volume of the operating fluid in its admission to the displacement zone may be adjusted to a nicety, or changed in proportion to the volume of liquid to be pumped in charges, owing to the interchangeable nature of the nozzles, one only of which is illustrated at 29, or the substitution of one for another having injector orifices of varying sizes.

55 The foregoing installation may continue to be employed until the production of the well has been materially decreased, and this

whether or not there has been an interchange or substitution of the nozzle element, but when such production has been substantially decreased, as inevitably follows with oil wells, then the well casing as the liquid 70 outlet conduit is substituted for by the introduction therein of the reduced liquid discharge pipe 32 and its gasket 33, which elements being lowered and properly set, at any desired position or distance from the pump, 75 will establish a thoroughly practical displacement zone or chamber and the size of which may be regulated or adjusted by the operator attendant, to meet varying conditions, by partially withdrawing or further 80 lowering of the pipe 32 with its gasket 33, as will be obvious.

In so far as pumping is concerned, the operations of the valvular mechanism of the modified constructions are the same as these 85 previously described, but in both of the modified arrangements there are no packer elements, the well casing forms no part of the displacement chamber, nor of the liquid discharge conduit, and the level of the 90 oil, therefore, would doubtless always extend substantially well up within the well casing, thus always supplying a substantial head of oil therein.

95 In installing the modified arrangement of Figure 3, the pumping unit is first lowered within the well casing, to the desired depth, by means of the attached liquid discharge pipe 40, after which the pressure fluid pipe 42 is introduced, down within the liquid discharge pipe, until its flanged or flaring lip 43 engages over the beveled edge 37, of the upstanding central tube 36, in fluid tight relation therewith.

100 In installing the modified arrangement of Figure 4, the pumping unit is lowered and supported by both the liquid discharge pipe 53 and the pressure fluid pipe 54, which are disposed alongside each other within the 105 well casing.

110 From the foregoing replete description, it is believed that the full objects and advantages of the invention will be clearly apparent, but, while there has thus been disclosed certain preferred embodiments 115 thereof, it may later be found to be expedient or desirable to make some alterations in the structural form and arrangement of parts, although without departing from the spirit of the invention. It is to be understood, therefore, that the invention is not to be restricted to all of the details exactly as disclosed, excepting as they may come within the terms of the claims, or equivalent combinations of elements, or as when fairly interpreted in the light of the specification if necessary.

115 What I do claim, as new and patentable, is:—

120 1. The combination with a pump casing 125

- embodying a chamber provided with a liquid inlet conduit, for communication with liquid under pressure to be pumped, liquid outlet means, and a displacing pressure fluid inlet conduit, the bore and discharge orifice of said fluid inlet conduit being of relatively smaller cross-sectional area than those of said liquid inlet conduit, of a valve in said chamber complementally coacting with said discharge orifices of said liquid inlet conduit and said fluid inlet conduit, under the opposing pressures therethrough, for closing the one while concurrently opening the other, the said valve automatically operating alternately in reverse directions upon a sufficient increase of counterbalancing pressure upon one surface thereof relatively to the pressure upon its opposite surface.
2. The combination with a pump casing embodying a chamber provided with a liquid inlet conduit, for communication with liquid under pressure to be pumped, liquid outlet means, and a displacing pressure fluid inlet conduit, the said liquid inlet conduit and the said fluid inlet conduit respectively providing for a discharge orifice that opens through a terminal valve seat thereof, which valve seats are substantially spaced apart and oppositely disposed within said chamber, and the said valve seat and discharge orifice of said fluid inlet conduit being relatively smaller than those of said liquid inlet conduit, of a valve freely operating between said seats in complemental coaction therewith, under the opposing pressures therethrough, for closing the one while concurrently opening the other, the said valve automatically operating alternately in reverse directions upon a sufficient increase of counterbalancing pressure upon one surface thereof relatively to the pressure upon its opposite surface.
3. The combination with a pump casing embodying a chamber provided with a liquid inlet conduit, for communication with liquid under pressure to be pumped, liquid outlet means, and a displacing pressure fluid inlet conduit, the discharge orifice of said fluid inlet conduit opening to said chamber being relatively smaller than the discharge orifice of said liquid inlet conduit opening to said chamber, of a valve freely operating between said discharge orifices in complemental seating coaction therewith, under the opposing pressures therethrough, for closing the one while concurrently opening the other, the said valve automatically operating alternately in reverse directions upon a sufficient increase of counterbalancing pressure upon one surface thereof relatively to the pressure upon its opposite surface.
4. The combination of a pump casing embodying a chamber provided with a lower liquid inlet conduit, for communication with liquid under pressure to be pumped, a head for said chamber having a bore therethrough, for coupling with a displacing pressure fluid inlet conduit, and its bottom being provided with a nozzle in communication with said bore and said chamber, the said nozzle terminating in a valve seat having the nozzle's discharge orifice opening therethrough, a lower valve seat within and in open communication with said liquid inlet conduit, being substantially spaced from and opposed to said other valve seat, the discharge orifice through the nozzle's valve seat being relatively smaller than the opening through said lower valve seat, liquid outlet means for said chamber, and a valve freely operating between said seats in complemental coaction therewith, under the opposing pressures therethrough, for closing the one while concurrently opening the other, the said valve automatically operating alternately in reverse directions upon a sufficient increase of counterbalancing pressure upon one surface thereof relatively to the pressure upon its opposite surface.
5. The combination of a pump casing embodying an open-ended chamber, a liquid inlet valve seat towards the lower end thereof, for open communication with said chamber and liquid under pressure to be pumped, a head for said chamber having a bore therethrough, for coupling with a displacing pressure fluid inlet conduit, and its bottom being provided with a nozzle in communication with said bore and said chamber, the said nozzle terminating in a valve seat having the nozzle's discharge orifice opening therethrough and being substantially spaced from and opposed to said other valve seat, the nozzle's valve seat discharge orifice being relatively smaller than the lower valve seat opening, liquid outlet means for said chamber, and a ball valve freely disposed between said seats and automatically operating, in complemental coaction therewith in reverse directions of movement, under the control of the alternately changing of relative pressures upon the upper and lower surfaces of said ball valve.
6. The combination of a pump casing embodying a chamber open at its lower end, a liquid inlet valve seat towards said lower end, for open communication with said chamber and liquid under pressure to be pumped, a head for said chamber having a bore therethrough, for coupling with a displacing pressure fluid inlet conduit, and its bottom being provided with a detachably connected nozzle, for interchangeable purposes, in communication with said bore and said chamber, the said nozzle terminating in a valve seat having the nozzle's discharge orifice opening therethrough and being opposed to said other valve seat in substantially spaced relation, the nozzle's discharge

orifice being relatively smaller than the lower valve seat opening, liquid outlet means for said chamber, and a valve freely operating between said seats.

5. 7. The combination of a pump casing embodying a chamber open at its lower end, a liquid inlet valve seat towards said lower end, for open communication with said chamber and liquid under pressure to be pumped, a head for said chamber having a bore therethrough, for coupling with a displacing pressure fluid inlet conduit, a nozzle detachably connected in association with said bore, in communication with said fluid inlet conduit and said chamber, the said nozzle being formed with a tapering bore merging into a terminating valve seat opposed to said other valve seat in substantially spaced relation, the nozzle's discharge orifice being relatively smaller than the lower valve seat opening, liquid outlet means for said chamber, and a valve freely operating between said seats.
- 10 15 20

8. The combination of a pump casing embodying a chamber open at its lower end, a liquid inlet valve seat towards said lower end, for open communication with said chamber and liquid under pressure to be pumped, a head for said chamber having a liquid outlet means therethrough and also a bore therethrough for coupling with a displacing pressure fluid inlet conduit, the lower end of said head providing for a nozzle projected into said chamber, which nozzle is adapted for communication with said fluid

inlet conduit and terminates at its projected end in a valve seat, through which the nozzle's discharge orifice opens, opposed to said other valve seat in substantially spaced relation, the nozzle's discharge orifice being relatively smaller than the lower valve seat opening, and a valve freely operating between said seats.

9. The method of pumping liquids, from a displacement zone supplied with the liquid under pressure, which employs an operating pressure fluid as a displacing fluid piston, and which includes the alternating steps of shutting off the inflow of said pressure fluid to said displacement zone concurrently with the admission of the liquid to be pumped, by virtue of the pressure of said liquid overbalancing an unobstructed constant pressure of said operating fluid, and reversely shutting off the inflow of said liquid to said displacement zone concurrently with the admission of said pressure fluid thereto, by virtue of the unobstructed constant pressure of said operating fluid overbalancing the pressure of said liquid, the cross sectional area of the volume of pressure fluid at its zone of entrance into said displacement zone being substantially less than the cross-sectional area of the volume of liquid at its zone of entrance into said displacement zone.

In testimony whereof, I affix my signature.

RALPH I. PENDLETON.
